UNITED STATES PATENT OFFICE.

WALTER H. BODURTHA, OF DELAWARE, OHIO, ASSIGNOR TO SUNRAY STOVE COMPANY, OF DELAWARE, OHIO.

COMBINED STOVE AND CABINET INTERCONNECTING MEANS.

Application filed December 31, 1925. Serial No. 78,618.

This invention relates to combination stoves and cabinets, and has more particular reference to a means for providing an insulating and ventilating connection therebetween for preventing the passage of the heat from the stove unit to the cabinet unit, and for permitting of the proper ventilation of the interior of the stove unit.

The primary object of the invention is to provide a relatively simple, novel, and cheap means whereby the units of a combined stove and cabinet may be properly interconnected for providing a single construction.

With the foregoing and other objects in view as the nature of the invention will be better understood, the same comprises the novel construction of interconnecting means hereinafter more fully described, shown in the accompanying drawing and claimed.

In the drawing wherein like reference characters indicate corresponding parts throughout the several views:

Figure 1 is a fragmentary vertical section through a combined stove and cabinet.

Figure 2 is a fragmentary transverse section through the stove and cabinet, and

Figure 3 is an enlarged fragmentary longitudinal section through the connecting means per se.

Now having particular reference to the drawing, the stove unit is fragmentarily shown in Figures 1 and 2, and designated 5 while the cabinet unit is similarly disclosed, and designated 6. The adjacent end walls 5' and 6' respectively of the units are adapted to be rigidly interconnected in spaced relation for providing an air channel 7 therebetween. The adjacent faces of said walls are entirely covered with a suitable heat insulating material 8, preferably asbestos or a substitute therefor. The interconnecting means for said end walls constitute the provision of a plurality of bolt and nut connections 9, there being provided between the wall carrying insulating strips suitable spacing insulating washers 10, Figure 1, that surround the bolts of the connection.

The bottom walls of the units 5 and 6 terminate at the end walls 5' and 6' respectively, in order that air may pass upwardly through the channel 7, and thence into the stove unit 5 by reason of said stove unit end wall 5' terminating slightly beneath the top wall 11 of said unit, Fig. 1. The end

wall 6' of the unit 6 extends completely up into engagement with the top wall 12 thereof for preventing the passage of the heat from the stove 5 to the cabinet 6.

The unit end walls 5' and 6' are formed at their forward edges with oppositely directed lateral extensions 5" and 6" respectively, Figure 3, over which the adjacent ends of the front walls 5^a and 6^a of the units 5 and 6 respectively, engage for providing a neat construction at the forward side of the combined stove and cabinet.

In order that the forward edges of the insulating material 8 upon the end walls will not be visible I provide metallic covering strips 8'-8' therefor of angle iron shape, as clearly shown in Figure 3, it being noted from a review of this figure that said insulating strips do not extend entirely to the front of the stove and cabinet units.

In order to prevent the conduction of the heat from the stove unit to the cabinet unit at the front sides thereof I provide a T-shaped strip 13, the web portion of which is provided with relatively large openings 14 through which the connecting bolts at the forward sides of the units extend, there being provided in this instance sectional spacing washers 10'-10' upon opposite sides of the web portion of said strip.

It will thus be seen that I have provided a highly novel and efficient form of connecting means between the units of a combined stove and cabinet that will effectively prevent the passage of the heat from the stove to the cabinet and that will permit of the proper ventilation of the stove unit and that will not detract from the appearance of the combined stove and cabinet.

Minor changes may be made in the invention without departing from the spirit and scope of the appended claims.

Having thus described the invention, what I claim as new and desire to secure by Letters Patent is:—

1. In a combined stove unit and cabinet unit wherein the same are disposed in adjacent end wall spaced relation, heat insulating strips disposed upon the adjacent sides of said end walls, means for interconnecting the end walls in spaced relation for providing an air channel therebetween, a T-shaped strip adapted to be disposed between the end walls at the front side thereof for substantially closing the space therebetween, the

- end wall of the stove unit being spaced from the top of the stove at the upper edge thereof in order that the air passing through the channel may enter the stove unit.
- 5 2. In a combined stove unit and cabinet unit wherein the same are disposed in adjacent end wall spaced relation, heat insulating strips disposed upon the adjacent sides of said end walls, means for interconnecting

the end walls in spaced relation for providing an air channel therebetween, and a T-shaped strip adapted to be disposed between the end walls at the front side thereof for substantially closing the space therebetween.

In testimony whereof I affix my signature.

WALTER H. BODURTHA.
